(57) **CLAIM**

The ornamental design for an accessory for portable electronic device, as shown and described.

DESCRIPTION

FIG. 1 is a top perspective view of an accessory for portable electronic device showing my new design;

FIG. 2 is a front view of the accessory for portable electronic device;

FIG. 3 is a back view of the accessory for portable electronic device;

FIG. 4 is a right side view of the accessory for portable electronic device;

FIG. 5 is a left side view of the accessory for portable electronic device;

FIG. 6 is a top view of the accessory for portable electronic device; and,

FIG. 7 is a bottom view of the accessory for portable electronic device.

The broken lines in the drawings depict environmental subject matter that forms no part of the claimed design.
